COMBINATION LAMP STAND AND
BOOK-RACKJohn P. Golden and Joseph F. O'Neil,
Waterbury, Conn.

Application October 30, 1934, Serial No. 750,664

9 Claims. (Cl. 211—43)

This invention relates to office or library furniture, and more particularly to a combination lamp stand and book-rack.

One object of this invention is to provide a combination lamp stand and book-rack of the above nature having a flat hollow base, a central lamp supporting standard, and a pair of slidable book-ends, together with spring means for urging said book-ends inwardly toward said lamp stand.

10 A further object is to provide a device of the above nature in which the book-ends are slidably positioned on the base at opposite sides of the lamp standard, and having means permitting said book-ends to be manually moved outwardly to provide a space or spaces for holding books, the spring means causing said book-ends to be automatically retracted when the books are removed from the rack.

20 A further object is to provide an article of furniture of the above nature which may be carried about as a unitary structure without removing or disturbing the books or lamp.

25 A further object is to provide a device of the above nature which will be simple in construction, inexpensive to manufacture, easy to install and manipulate, compact, very ornamental in appearance, and very efficient and durable in use.

With these and other objects in view, there has 30 been illustrated on the accompanying drawings, one form in which the invention may be conveniently embodied in practice.

In the drawings:

Fig. 1 represents a side elevation of the combination lamp-stand and book-rack as it appears with the book-ends in closed position.

Fig. 2 is a plan view of the same with the upper part of the lamp standard shown in section.

Fig. 3 is a bottom plan view of the supporting plate as it appears when removed from the base.

Fig. 4 is a fragmentary transverse sectional view of the invention, taken along the line 4—4 of Fig. 2, looking in the direction of the arrows.

Fig. 5 is a perspective view of the invention as 45 it appears with the book-ends held spaced from the center of the standard.

50 Referring now to the drawings in which like reference numerals denote corresponding parts throughout the several views, the numeral 10 indicates a flat elongated base preferably made of wood or reinforced molded composition, and having a hollow top section 11. A pair of stepped portions 12 are located at the opposite ends of the hollow top section 11 in order to form a seat for 55 a supporting plate 13, preferably made of metal.

The plate 13 is elevated above the stepped sections 12 by a pair of small interposed bolster rods 14, affixed to the underside of said plate 13 at the opposite ends thereof. The supporting plate 13 is adapted to be held securely upon the base 10 as by means of four screws 15 located at the opposite corners of said plate 13 and engaging in the stepped sections 12.

5 Located directly in the center of the supporting plate 13 is a vertical lamp standard 16, carrying on its upper end a conventional electric light socket 17. The central standard 16 is preferably made of square tubing, and is supported at its lower end by a pair of side wings 18 and 19 rigidly secured thereto, as by soldering. The side wings 18 and 19 are preferably made in the form of buttresses of progressively decreasing heights.

10 In order to attach the central standard 16 and its integral wings 18 and 19 to the base, provision is made of a piece of round tubing 20 located 15 within the standard 16, and having threaded engagement with the end bushing 21 of the light socket 17 in the usual manner. The bushing 21 is preferably supported upon an enlarged square block 21a resting upon the upper end of the lamp standard 16. The lower end of the round tubing 20 is threaded and extends through a suitable aperture in the supporting plate 13, where it receives a nut 22, which when tightened up, will bind the standard 16 and side wings 18 and 19 20 tightly against the top surface of the plate 13.

25 The tubing 20 serves as a conduit for a two-wire electric cable 23, one end of which is connected with the electric socket 17, while the other end of said cable is directed out through 30 a suitable aperture 22a in the base 10. The outer end of the cable 23 is provided with a suitable prong plug 24 or an analogous device for connecting the lamp into an electric circuit.

35 In order to provide guideways for a pair of sliding plates 25 and 26, the opposite longitudinal edges of the supporting plate 13 are provided with a pair of raised integral flanges or rails 27 and 28.

A pair of ornamental T-shaped book-ends 29 and 30 are mounted upon the plates 25 and 26, 40 respectively. As best shown in Figs. 2 and 5, each book-end comprises a series of buttresses of progressively decreasing heights, shaped to harmonize with the design of the wings 18 and 19. The inner flat faces of the book-ends 29 and 30 45 are indicated by the numerals 31 and 32.

50 The opposite ends of the sliding plates 25 and 26 are provided with a pair of depending integral U-shaped clips 33 and 34, which embrace the rails 27 and 28 of the supporting plate 13, and 55

5 terminate in a pair of depending staggered flanges 35 and 36, extending downwardly into the cavity 11 of the base 10 (see Fig. 4). In order to permit the sliding plates 25 and 26 to move freely without frictional resistance, clearance slots 37 and 38 are provided between the rails 27 and 28 and the side walls of the cavity 11.

10 For the purpose of holding the book-ends 29 and 30 normally in the closed position shown in Figs. 1 and 2 against the base of the standard 20 when no books are stacked on the base 10, or to press inwardly against the books when the device is used as a book-rack, provision is made of 15 two pairs of helical tension springs 39 and 40, attached to the inner ends of the sliding plates 25 and 26 and the outer portions of the supporting plate 13, respectively. For this purpose, both 20 ends of each spring are provided with loops 41 and 42, the inner loops 41 engaging in suitable apertures in the depending flanges 35, 36 of the plates 25 and 26, while the outer end loops 42 engage about a pair of studs or posts 43 and 44 depending from the underside of the supporting 25 plate 13. The studs or posts 43 and 44 are preferably formed by bending the ends of a pair of square bars 45 and 46, and said bars may be securely fastened to the underside of the supporting plate 13 as by soldering.

30 While there has been disclosed in this specification one form in which the invention may be embodied, it is to be understood that this form is shown for the purpose of illustration only, and that the invention is not to be limited to the 35 specific disclosure but may be modified and embodied in various other forms without departing from its spirit. In short, the invention includes all the modifications and embodiments coming within the scope of the following claims.

40 Having thus fully described the invention, what is claimed as new, and for which it is desired to secure Letters Patent, is:

45 1. In a book-rack, a base, a central fixed standard, a pair of plates slidable on said base on opposite sides of said standard, a pair of book-ends being mounted on said plates, and means connected to both ends of said base for normally urging said book-ends inwardly toward said standard.

50 2. In a book-rack, a base having a hollow rectangular top section, a supporting plate mounted on said base and bridging said hollow section, a fixed standard centrally mounted on said base, a pair of book-ends slidably mounted on said plate on opposite sides of said standard, and spring means for normally holding said book-ends inwardly against said standard or against any books which may be interposed therebetween, said spring means passing under said standard and connected to the ends of said hollow base.

55 3. In a book-rack, a hollow base, a supporting plate mounted on said base, a standard mounted on said plate, a pair of book-ends slidably mounted on said supporting plate on opposite sides of said standard, and spring means located in said base and connected to said book-ends for normally urging said book-ends inwardly against

5 said standard or any books which may be interposed between said standard and said book-ends, said spring means passing under said standard and connected to the ends of said hollow base.

4. In a book-rack, a hollow base, a rigid supporting plate mounted on said base leaving slots along the side edges thereof, a standard mounted on said plate, a pair of sliding plates mounted on said rigid plate, said sliding plates having 10 clip means located in said slots and embracing the longitudinal edges of said rigid plate, book-ends mounted on said sliding plates, spring means located in said base and attached to said clip means and the ends of said base, whereby 15 said book-ends will be normally pressed inwardly against said standard or any interposed books.

5. In a book-rack, a hollow base, a supporting plate mounted on said base having slots along the side edges thereof, a standard mounted on 20 said base, a pair of sliding plates mounted on said plate, said sliding plates having clip means located in said slots and embracing the longitudinal edge of said plate, book-ends mounted on said sliding plates, spring means located in said 25 base and attached to said clip means and the ends of said base whereby said book-ends will be normally pressed inwardly against said standard or any interposed books.

6. In a book-rack, a base, a rigid standard 30 mounted upon said base, a book-end slidably mounted on said base near one end thereof, and spring means for urging said book-end against said standard, said spring means being secured at one end to said book-end, passing under said 35 standard, and anchored at its other end to the opposite portion of said base from said book-end.

7. In a book-rack, a base having a hollow rectangular top section, a supporting plate having upstanding guide rails mounted on said base and 40 bridging said hollow section, a rigid standard centrally mounted on said base, a pair of book-ends slidably mounted on said rails on opposite sides of said standard, and a pair of spring means for normally holding said book-ends inwardly 45 against said standard or against any books which may be interposed therebetween, each of said spring means being connected to the outer ends of said base.

8. In a book-rack, a base adapted to rest upon 50 a table, a pair of book-ends slidably mounted on said base, and springs secured to each book-end passing under the other book-end, and anchored to the opposite end of said base therefrom.

9. In a book-rack, a base having a hollow rectangular top section, a supporting plate mounted on said base and covering said hollow section, a pair of book-ends slidably mounted on said plate, said book-ends having depending flanges, and a pair of helical springs attached to said 60 flanges for normally urging said book-ends toward the center of said plate, said springs passing under said plate and being connected to the opposite ends of said base.
